UNITED STATES PATENT OFFICE

DEWEY H. BITNEY, OF ALBION, MICHIGAN, ASSIGNOR TO UNION STEEL PRODUCTS COMPANY, OF ALBION, MICHIGAN

STRUCTURAL UNIT

Application filed April 29, 1929. Serial No. 358,785.

The main objects of this invention are to provide a combined reinforce spacer and support which is adapted to be made in strips of considerable length and cut into the desired units or sections and one in which the reinforce bars may be engaged with a "snap" action and at the same time are very securely retained.

A further object is to provide a structural unit having these advantages which may be very economically produced and is very convenient in use.

Objects relating to details and economies of my invention will appear from the description to follow. The invention is defined and pointed out in the claims.

A structure which is a preferred embodiment of my invention is illustrated in the accompanying drawing, in which:

20 Fig. 1 is a fragmentary perspective view of a structural unit embodying the features of my invention, a reinforcing bar being indicated in engagement therewith by dotted lines.

25 Fig. 2 is a fragmentary side elevation, the reinforcing bars being indicated by dotted lines.

Fig. 3 is an end view of my improved structural unit, a reinforcing bar being indicated by dotted lines.

30 My improved structural unit comprises a longitudinal rod 1 which may be of considerable length and a plurality of combined legs, struts and reinforce bar engaging members which are secured to the rod in spaced relation. These combined legs, struts and reinforce engaging members are formed integrally of wire or light rod, each consisting of 35 a pair of legs 2 which are fixedly secured to the rod as by welding, with their upper ends projecting substantially above the rod. The upper ends of the legs are connected by a down-turned loop 3 constituting a strut and 40 an engaging member for the reinforce bar, as 4. The arms of the loop are outwardly offset at 5 in approximately the plane of the longitudinal rod. The arms of the loop converge upwardly above this offset so that when 45 the rod is forced downwardly between the

arms to rest upon the longitudinal rod, it is retained in position thereby.

The upper ends of the legs are connected to the arms of the loop by downwardly converging portions 7 providing a flaring throat 55 for the legs so that the reinforcing bars may be engaged by laying them in these throats and pushing downwardly thereon, the arms of the loops springing open to receive the same and closing to retain them. This engagement may be effected without loosening the connection of the legs to the longitudinal rod.

The rod retaining loops serve as effective braces or struts for keeping the supports in 60 upright position both before and after the reinforce bars are engaged therewith and the supports are not likely to be distorted by workmen walking upon the bars during the process of construction.

I have illustrated and described my improvements in a very simple and practical embodiment. I have not attempted to illustrate or describe certain modifications or adaptations as I believe this disclosure will 65 enable those skilled in the art to embody or adapt my improvements as may be desired.

Having thus described my invention, what I claim as new and desire to secure by Letters Patent, is:

1. A structural unit comprising a longitudinal rod and a plurality of pairs of legs fixedly secured to the rod in spaced relation with their upper ends projecting substantially above the rod, the upper ends of the legs being connected by an integral down-turned loop constituting a strut, the arms of the loop being outwardly offset in approximately the plane of the longitudinal rod and being converged upwardly from such offsets providing yielding bar engaging members, the upper ends of the legs being connected to the arms of the loop by downwardly converging portions providing a flaring throat 85 for the loop.

2. A structural unit comprising a longitudinal rod and a plurality of pairs of legs fixedly secured to the rod in spaced relation with their upper ends projecting substantially above the rod, the upper ends of the 90

legs being connected by an integral down-turned loop constituting a strut, the arms of the loop being outwardly offset in approximately the plane of the longitudinal rod and being converged upwardly from such offsets providing yielding bar engaging members.

3. A structural unit comprising a longitudinal supporting rod, and a plurality of 10 pairs of legs fixedly secured to the rod in spaced relation with their upper ends projecting substantially above the rod and connected by an integral down-turned loop constituting a strut and a reinforce engaging 15 means.

4. A structural unit comprising a longitudinal rod and a pair of legs fixedly secured to the rod with their upper ends projecting substantially above the rod, the upper ends 20 of the legs being connected by an integral down-turned loop constituting a strut, the arms of the loop having outward offsets therein and being converged upwardly from such offsets providing yielding bar engaging members, the upper ends of the legs being connected to the arms of the loop by downwardly 25 converging portions providing a flaring throat for the loop.

5. A structural unit comprising a longitudinal rod and a pair of legs fixedly secured to the rod with their upper ends projecting substantially above the rod, the upper ends of the legs being connected by an integral down-turned loop constituting a strut, 35 the arms of the loop having outward offsets therein and being converged upwardly from such offsets providing yielding bar engaging members.

6. A structural unit comprising a longitudinal supporting rod, and a pair of legs fixedly secured to the rod with their upper ends projecting substantially above the rod and connected by an integral down-turned loop constituting a strut and providing an 45 upwardly facing slat-like reinforce engaging means.

In witness whereof I have hereunto set my hand.

DEWEY H. BITNEY.
